METHOD OF MAKING SOUND REPRODUCING
DIAPHRAGMS

Spencer W. McKellip, Philadelphia, Pa., assignor
to Philadelphia Storage Battery Company,
Philadelphia, Pa., a corporation of Pennsylvania

Application June 10, 1932, Serial No. 616,552

6 Claims. (Cl. 18—56)

This invention relates to conical sound reproducing diaphragms and to methods of making such diaphragms, the general object being to provide a novelly constructed diaphragm by means 5 of a novel method.

A more specific object of the invention is to provide a diaphragm having improved frequency response characteristics and which readily lends itself to variation of such characteristics during 10 manufacture.

A further object of the invention is to provide a diaphragm which is mechanically durable and which will retain its original shape indefinitely.

A still further object of the invention is to provide 15 a conical diaphragm formed in one piece from a single blank of material.

Another object of the invention is to provide a conical diaphragm which readily lends itself to economical manufacture.

20 A further and more specific object of the invention is to provide a method of forming a peripheral corrugated flange on a preformed conical diaphragm without weakening or breaking down the fibres of the paper or other material from which 25 the diaphragm may be made.

Other objects of the invention will appear hereinafter. Reference may be had to the following detailed description and accompanying drawings for a full and complete disclosure of the 30 invention.

In the drawings:

Fig. 1 is a sectional view illustrating the general construction of my improved diaphragm and the manner in which such diaphragms are com- 35 monly supported;

Fig. 2 illustrates three different forms which the peripheral corrugated flange of the diaphragm may take;

Fig. 3 is a face view of a blank of material from 40 which the conical diaphragm may be formed;

Figs. 4 to 7 illustrate diagrammatically the manner in which the peripheral portion of the conical diaphragm is press-shaped to form the desired corrugated flange, these figures showing 45 successive stages of the operation; and

Fig. 8 is a sectional view of apparatus in the form of a press for imparting the desired shape to the diaphragm after it has been preformed.

Various attempts have been made to provide 50 one-piece conical diaphragms, but up to the present time, the resulting products have been more or less unsatisfactory. An attempt has been made to provide a satisfactory diaphragm by pre-forming a cone and providing the desired corrugated flange around the periphery thereof by bending. This method has proven unsatisfactory, however, due to various reasons which need not be pointed out in detail. It suffices to state that this method of forming the diaphragm results in weakening or even breaking down of the

fibres of the peripheral portion, thereby preventing the attainment of a satisfactory product from the standpoint of efficiency of operation and mechanical durability.

In accordance with the present invention, I 5 provide a conical diaphragm which is superior to any such diaphragms as have been made heretofore including those mentioned above. It is known that the provision of corrugations in the body of the diaphragm at the same time that the flange is formed is desirable in some instances. The essential feature of the invention is, however, the method of forming the corrugated peripheral flange which, as is now commonly known, serves 10 to resiliently and flexibly mount the diaphragm on its support. The method consists essentially in preforming a cone and then press shaping the peripheral portion to provide the desired corrugated flange.

Referring to the drawings and particularly to Fig. 1, there is illustrated in this figure a diaphragm 1 constructed in accordance with the invention, preferably having corrugations 2 in the conical body portion thereof and having a corrugated peripheral flange 3. The outer part 4 of this flange is flat so that it may be clamped to the usual support 5 by means of clamping ring 6.

I have found that the frequency response characteristics of a diaphragm depend upon various features, the chief ones of which are the constituency of the material from which the cone is made, the angle of the cone, the corrugations of the peripheral flange, and the method of transforming the cone into the finished product. The first of these features deals, of course, with the manufacture of the paper or other material of which the diaphragm is made, and any particular frequency characteristic may be had within a wide range by modifying the constituent elements of the material and the method of making such material. The angle of the cone depends, of course, upon the design and obviously this feature may be modified at will in the making of the diaphragm. The corrugation of the peripheral flange may also be varied to impart different frequency response characteristics to the diaphragm.

In Fig. 2 of the drawings, there are disclosed three types of corrugations, the uppermost being a "double" corrugation, the central one being a "single" corrugation, and the lowermost being a "triple" corrugation. By varying the number of corrugations in the flange, the flexibility of the diaphragm mounting may be varied to, in turn, vary the frequency response characteristic. While any number of corrugations may be provided, I prefer to use the "double" corrugation illustrated in Fig. 2 since I have found that this form gives a desired degree of flexibility and at the same time has no tendency to stretch or distort the fibres of the material. I have also found 55 60

that a smooth or continuously curved corrugated surface is much better, both from the standpoint of mechanical strength and efficiency of operation, than is a surface having ridges or creases. 5 I, therefore, contemplate the forming of the corrugated surface as a smooth one throughout.

Coming now to the novel method which forms the essential part of the present invention, the first step is to provide a blank of desired shape 10 from suitable material. Any desired and suitable material may be used, but preferably some type of paper is used to make the diaphragm. Assuming that sheet material having the desired structure has been decided upon, a blank 7 (see Fig. 15 3) is formed from such material in any desired manner such, for example, as by cutting. It will be noted that this blank is circular in shape and has a sector removed therefrom, as at 8, as well as a central opening 9. Having provided 20 such a blank, a cone is then formed therefrom by attaching the radial edges 10 of the blank by any suitable means, such as cement. While any particular cement may be used, I prefer to use pyroxylin cement applied to both the radial edges 25 which is first allowed to dry out and then a thinner coat applied to the edges to soften the cement and enable the desired adhesion by heating and pressure. In any event, care should be exercised in the selection of cement, since inferior cement 30 might cause the cone to buckle or warp.

The next step is to moisten the peripheral portion of the cone which is to be press-shaped in the manner described hereinafter to form the corrugated flange. This is a very important step 35 which must be carefully performed if successful results are to be obtained. The cone may be moistened all over particularly when corrugations are to be impressed on it. While any suitable moistening agent may be used, I prefer to use a 40 solution of water and denatured alcohol, the solution containing about 25% alcohol when a small percentage of sizing is contained in the paper cone. If desired, a small quantity of stearic acid and ammonium hydroxide may be added to 45 the solution to waterproof it. The quantity of this mixture may be about 2% of the entire solution.

The final step in the method is to provide the corrugated peripheral flange on the cone and this I do by a method which I prefer to term "press shaping". The diagrammatic illustration of Figs. 4 to 7 shows clearly the manner in which this 50 step of the method is carried out. Referring to those figures, 11 designates a lower stationary ring-shaped die member. 12 designates an upper 55 movable die member having a conical surface 13, which die member is adapted to co-act with member 11 to form the corrugated flange on the cone, the two die members being provided with machined corrugational surfaces 14 and 15, respectively. A central movable plug 17 is slidably positioned within the lower die member and has its upper end formed, as at 18, to conform with the conical surface of the diaphragm and with the surface 13 of die member 11. The purpose 60 of this illustration is to clearly disclose the manner in which the shaping of the peripheral flange is obtained and not to disclose a practical apparatus for carrying out this step, such apparatus being disclosed in Fig. 8 to be described later.

70 Referring still to Figs. 4 to 7 and considering the manner in which the peripheral flange is formed, die member 12 is raised sufficiently to allow the positioning of the diaphragm 19 on the plug 17, as shown in Fig. 4. Die member 12 is 75 now brought forcibly downward against the dia-

phragm whose central body portion is held rigidly between member 12 and plug 17. Die member 12 and plug 17 are then moved downward and in doing so member 12 co-acts with the die member 11 to provide the desired corrugated flange. It must be remembered that, the cone has had its peripheral portion moistened, as set forth above, so as to render it more susceptible to the shaping process. It is important to note that the corrugated flange is not embossed in the present method. What actually takes place when die member 12 and plug 17 are moved downward, is that when the peripheral edge portion of the cone engages die member 11, it snaps back as illustrated in Fig. 4. As the die member 12 and plug 17 are moved further down the rounded portion 20 engages the portion 20a of the die member 11, (see Fig. 5), and the flange is caused to take the shape illustrated in Fig. 6. The flange takes a corrugational form approximating the corrugational 20 surfaces of the dies. The approximate corrugational shape is thus imparted to the peripheral portion of the cone without any embossing and consequent stretching of the material taking place, the periphery being preformed, so to speak, 25 as die member 12 descends. Pressure is applied to the preshaped cone by the dies, as shown in Fig. 7.

In Fig. 8, there is illustrated apparatus which operates according to the above-discussed principles to form the cone. It will be understood, of course, that any suitable apparatus may be used, the illustrated apparatus of Fig. 8 being merely one form of apparatus which may be used to perform the method. The apparatus comprises 30 essentially a lower stationary ring-shaped die member 21, an upper movable die member 22, and a central movable plug 23, these elements corresponding respectively to elements 11, 12 and 17 of the diagrammatic illustrations of Figs. 4 to 7. 35 Preferably, the conical surfaces of die member 22 and plug 23 are corrugational as illustrated, to impart to the central or body portion of the cone a corrugated surface which has been found to 40 enhance the operation of the diaphragm as previously stated. 45

Die member 22 comprises body 24 and ring 25 attached thereto. Body 24 is formed so as to provide a steam chamber 26 for heating the die member, it being understood that steam or other suitable heating medium is supplied to the chamber from a suitable source. Body 24 is suspended from support 27 and the entire assembly is movably mounted for cooperation with the movable plug 23 and the stationary die member 21. A recess 28 is provided in body 24 at the apex of the conical surface thereof and a plug 29 is centrally located in the recess. The apex of plug 23 is provided with a guide recess 30 for plug 29, the recess being formed in plug 31 forming the apex of the plug 23. The extended portion 32 of plug 31 is received by recess 28, during operation of the device, to form the voice coil supporting collar of the diaphragm. Normally, the movable die assembly is spaced from plug 23 such a distance as to enable the placing of the diaphragm 19 in inverted position over the plug as illustrated. At this time, plug 23 is in its uppermost position, being normally urged to that position, as will appear more clearly hereinafter. 55

The stationary ring-shaped die member 21 is carried upon body 33 also formed to provide a steam chamber 34. Plug 23 is adapted to move slidably within the die member and body 33. The plug is carried at the upper end of shaft 35, which 60 65 70 75 75

is slidably mounted in bushing 36 and stationary collar 37. The shaft has attached thereto a collar 38. A coil spring 39 surrounds the shaft and is interposed between collars 37 and 38. Thus 5 spring 39 normally urges the plug to its uppermost position, this action being limited by engagement of collar 38 with supporting plate 40.

In order to provide for the attachment of a 10 cardboard or like ring 41 to the peripheral flange of the cone during the press-shaping operation, there is provided a supporting ring 42 which is resiliently mounted upon springs 43, these springs being carried by studs 44 having their lower ends 15 threadedly secured in flange 45 of body 33.

15 In operation, the diaphragm is placed in inverted position upon plug 23, as above stated. If ring 41 is to be attached to the diaphragm, it is placed in position upon ring 42. The upper die assembly is now moved downward and die 20 member 22 contacts the diaphragm to firmly hold the body thereof and to emboss the body corrugations therein, as the upper die assembly together with plug 23 now move downward and the 25 press-shaping of the peripheral portion of the diaphragm is had in the manner above described with reference to Figs. 4 to 7. At this time, ring 41 is firmly secured to the diaphragm, it being understood that a suitable adhesive will be applied to the ring or diaphragm to effect this result. 30 After the diaphragm is properly shaped, the upper die assembly is moved upward to a position where the diaphragm may be removed. It should be noted, however, that the corrugations formed in the body of the cone by plug 23 and die member 22 involve an embossing of the diaphragm as 35 distinguished from the shaping of the outer peripheral flange.

It will be apparent from the present disclosure 40 that the novel method of the invention enables the making of conical diaphragms having the various desirable characteristics hereinbefore mentioned. Obviously, various changes and modifications in the method, as well as the product, may be resorted to without departing from the scope of the invention so long as the principles 45 set forth herein are retained. It is to be understood then that the appended claims define the scope of the invention.

I claim:

50 1. A method of making a conical sound reproducing diaphragm, which comprises preforming a member with a conical peripheral portion from flexible non-brittle fibrous sheet material, supporting said member throughout substantially the entire area of its body leaving only its peripheral portion free, applying a force to the edge of said portion by ground die members to cause the edge to turn back, applying a second force by said die members to the turn thus produced, applying a third force by said die members to the edge in a direction opposite that of the first two forces, whereby the peripheral portion is caused to assume an approximate corrugational flange shape, and pressing said portion 55 into a desired corrugational flange shape.

70 2. A method of making a sound reproducing diaphragm, which comprises forming a conical member from flexible non-brittle sheet material, applying a force to the annular peripheral edge of said member over the entire area of said edge in a direction to cause the edge to snapingly turn back toward the body of said member, applying subsequent forces in the presence of re-

sisting forces by grooved die surfaces to areas of said member inward of its peripheral edge and in the vicinity of the turned back portion to cause said portion to assume an approximate corrugational flange shape, and pressing said portion by 5 the grooved die surfaces into desired corrugational flange shape.

3. A method of making a sound reproducing diaphragm, which comprises preforming a member with a conical peripheral portion from flexible 10 non-brittle fibrous sheet material, supporting said member throughout substantially the entire area of its body leaving only its peripheral portion free, applying a force to an outer annular area of the peripheral portion by grooved die 15 members, applying a subsequent force to an inner annular area of said portion in the presence of a resisting force by said die members to cause said portion to assume an approximate corrugational flange shape, and pressing said portion 20 into a desired corrugational flange shape.

4. A method of making a sound reproducing diaphragm, which comprises preforming a member with a conical peripheral portion from flexible 25 non-brittle fibrous sheet material capable of being softened by moistening, moistening said portion, supporting said member throughout substantially the entire area of its body leaving only its peripheral portion free, applying a force to an outer annular area of the peripheral portion 30 by grooved die members, applying a subsequent force to an inner annular area of said portion in the presence of a resisting force by said die members to cause said portion to assume an approximate corrugational flange shape, and pressing 35 said portion into a desired corrugational flange shape.

5. A method of making a sound reproducing diaphragm, which comprises preforming a member with a conical portion from flexible non- 40 brittle fibrous sheet material, embossing the inner part of said portion so as to provide concentric corrugations therein, supporting said member throughout substantially the entire area of its body leaving only the outer part of said 45 portion free, applying a force to an outer annular area of said outer part by grooved die members, applying a subsequent force to an inner annular area of said outer part in the presence of a resisting force by said die members to cause 50 said outer part to assume an approximate corrugational flange shape, and pressing said outer part into a desired corrugational flange shape.

6. A method of making a sound reproducing diaphragm, which comprises preforming a member with a conical portion from flexible non- 55 brittle fibrous sheet material capable of being softened by moistening, moistening said portion, embossing the inner part of said portion so as to provide concentric corrugations therein, supporting said member throughout substantially the entire area of its body leaving only the outer part of said portion free, applying a force to an outer annular area of said outer part by grooved die members, applying a subsequent 60 force to an inner annular area of said outer part in the presence of a resisting force by said die members to cause said outer part to assume an approximate corrugational flange shape, and pressing said outer part into a desired corruga- 65 tion flange shape.
